United States Patent Office

Des. 217,237

Patented Apr. 21, 1970

217,237

INFORMATION-CENTER BUILDING

Henry L. Lawshe, Fort Collins, Colo., assignor to Travel, Incorporated, Fort Collins, Colo., a corporation of Delaware

Filed May 26, 1969, Ser. No. 17,362

Term of patent 14 years

Int. Cl. D25—04

U.S. Cl. D13—1

FIG. 1

FIG. 2

FIG. 4

FIG. 3

FIG. 1 is a plan view of an information-center building incorporating the design of the present invention;

FIG. 2 is a front-elevational view of the building of FIG. 1;

FIG. 3 is a side-elevational view of the building of FIG. 1; and

FIG. 4 is a perspective view of the building of FIGS. 1, 2 and 3.

Except for presenting an overall outline like that shown in FIG. 2, the rear of the building is unornamental and thus is not separately shown.

I claim:

The ornamental design for an information-center building, as shown and described.
